COMBINATION CONTAINER AND ROLLER PAN

John Lo Verde, Rochester, N. Y.

Application February 1, 1954, Serial No. 407,278

4 Claims. (Cl. 15—121.2)

This invention relates to a paint container for roller applicators, and more particularly to a combination paint container and roller applicator pan adapted to drain into the container when in use or to act as a carrying means for transporting the container.

The application of paint by rollers having lamb's wool or similar coating in place of brushes has expanded to a considerable extent in the industry. In the application of paint by the roller applicator method, it is necessary to have a relatively broad container, sufficient to receive a roller having a length of six or more inches. It is further necessary to submerge the roller to a considerable extent within the paint contained within the container, so that paint containers for roller application have taken on the aspect of broad shallow pans. Such pans are cumbersome, and have generally been provided with one side formed as an inclined drain surface extending from below the level of the paint contained therein to a point above the level, the latter for the purpose of providing an exposed surface upon which the roller may be rolled to spread the paint applied to the roller uniformly over the entire roller circumference and length. Such inclined drain surfaces have interfered with the quantity of paint which it is possible to place within the pan, and the apparatus in general has been found cumbersome and difficult to handle, and liable to result in spillage.

The present invention is directed to a paint container of shallow depth and wide cross-section, and the provision of a drain pan therein which may be placed in an inclined position so as to act as a drain tray or which may, for transport purposes, be erected to a vertical position so as to operate as a handle. The tray is such as to avoid interference with the container, so that the container may hold a maximum of paint. The invention further has to do with mechanism for rendering it possible to shift the drain tray from an inclined draining position to an upright position, where it may act as a handle, and vice versa, in a handy manner, and providing means whereby when in the handle position, the parts are locked so as to preclude tilting of the container.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a perspective view of the paint container;

Figure 2 is a sectional view taken on a vertical plane showing the paint container with the tray in an inclined position;

Figure 3 is a view similar to Figure 2, in which the tray is shown in upright handle transport position;

Figure 4 is a rear elevational fragmentary sectional view of the container, showing the tray and a preferred

2

form of the locking mechanism, taken substantially on the line 4—4 of Figure 3:

Figure 5 is a fragmentary sectional view taken substantially on the line 5—5 of Figure 3;

Figure 6 is a sectional view taken substantially on the line 6—6 of Figure 3; and

Figure 7 is a view similar to that shown in Figure 4, in which a modified locking device is shown.

Referring to the drawings, and particularly Figures 10 2—4, there is shown a somewhat shallow paint container 10, having side walls 12 and 14, and end walls 16 and 18. The width of the container is preferably chosen sufficiently great in order to receive the roller of a roller coating device or applicator as is customarily employed for applying various paints by the roller applicator method. The container may be of a size sufficient to hold two quarts or a gallon of paint, without filling the same more than approximately half full. Such container may be drawn from a single sheet of metal or plastic, and the various surfaces thereof may be ribbed or otherwise strengthened so as to permit usage of light gage materials. The side walls 12 and 14 are provided centrally thereof and along the upper edge thereof with plates 20 and 22, forming ears to which is pivotally secured a drain or roller pan 24. Such drain pan comprises a broad bottom 26, side members or flanges 28 and 30, and an end member or flange 32 remote from the pivots 34 and 36 between the side flanges 28 and 30 and the plates 20 and 22. The plates 20 and 22 are provided with 20 inwardly bent stops 38 and 40 which are adapted to limit the pivotal or angular movement of the pan when moving the pan to the position shown in Figure 3.

In order to hold the pan in an erect position as shown in Figure 3, there is provided on the back face of the 30 pan a suitable locking mechanism, positive in character as more particularly shown in Figure 4. The plates 20 and 22 are provided with a pair of slots 42 and 44 located immediately to the rear of the bottom of the tray 24 when in erect position. On the underneath side of 40 the bottom 26, there is provided a resilient heavy V-wire 46 adapted to slide in loops 48 and 50 and guides 52 and 54, such V-wire being provided with a lateral U-bend 56 at the apex thereof to provide a finger grip to afford easy manipulation of the wire as will presently appear. It 45 will be seen that upon movement of the lateral U-bend portion of the wire by finger pressure to the dotted line position shown at 56', the flanks 58 and 60 of the V-wire are drawn together and the tip ends 62 and 64 of such wires are withdrawn toward one another so as to be positioned free of the slots 42 and 44.

When the wire lock is thus moved to a retracted position, the pan may be moved from the position shown in Figure 3 to the position shown in Figure 2, wherein the 55 bottom surface 26 becomes ideally suited for use as a drainboard against which the roller coating device may be lightly rolled in order to uniformly distribute the paint throughout the circumference of the roller and remove excess paint. Thus, in practice, the roller of the 60 roller coating device may be dipped in the supply of paint with little regard to over-saturation of the roller coating fabric or absorbent surface, and thereafter rolled upon the inclined drain pan surface 26. Thus, the excess paint is squeezed from the surface and uniformly distributed throughout the roller circumference before applying the 65 roller to the surface being painted. In this manner, it is possible to avoid having an excess quantity of paint on the roller which would be liable to drip or splatter, or otherwise provide an uneven effect in application. The incline of the pan provides for drainage of the excess paint into the container, and thus the apparatus is capable of being used in such a way as to render it relatively 70 easy to control the quantity of paint upon the roller coat-

ing device without requiring any particular care as to the manner of dipping the roller within the container supply.

Underneath the drain tray, there may be provided a removable shelf 66 having turned up end portions 68 and 70 which are suitably flanged as at 72 and 74 to embrace the upper turned over rim or edge of the side walls 12 and 14. Such tray may support a roller paint applying device during transport of the container.

It will be seen from the foregoing that there is provided a shallow paint container adapted to hold large quantities of paint, and that provision is made whereby such container may be transported without danger of tipping and spillage. When the drain pan is in the upright position as shown in Figure 3, and the bucket carried by the handle 76, it is evident that swinging motions and other motions likely to occur during carrying such a container on scaffolding and ladders or the like will be such as to not likely cause spillage of paint contained in the container, for the reason that the pendulum action permits the container to swing with the paint contained therein. When a painter transports the device to a work position through the manipulation of the finger loop 56 and sets the container upon a relatively even surface, the pan is shifted to the inclined position shown in Figure 2. It will be seen that as the pan is shifted to the inclined position, the ends 62 and 64 of the resilient wire 46 ride upon the inside face of the plates 20 and 22. Conversely, as the pan is moved from the position shown in Figure 2 to the position shown in Figure 3, the ends 62 and 64 snap into the slots 42 and 44 as soon as the pan reaches the vertical position shown in Figure 3.

In Figure 7, there is shown an alternative locking device comprising transverse bars 78 and 80, pivoted together as at 82 and connected to a manual central operating bar 84, the manual operating bar extending upward and being provided with a handle 86 at its upper end in the region of the carrying handle 76. The bar 84 is slidably mounted in loop members 88 and 90 spot welded or otherwise secured to the pan bottom 26. The bars 78 and 80 are provided with slots 92 and 94 in their ends, which slots ride upon pins 96 and 98 affixed to plates 100 and 102 spot welded or otherwise secured to the bottom 26. A spring 103 is connected between the pin 82 and the loop member 90, and a stop pin 104 and the bar 84 may be so positioned as to engage the bracket member 88 and limit the upward movement of the manipulating bar 84. The ends 106 and 108 of the bars 78 and 80 are adapted to project into the slots 42 and 44 in the same manner as the ends 62 and 64 of the wire 46 in the modification of Figure 4. When it is desired to move the pan from the vertical position to the horizontal position, the manipulating bar 84 is moved downwardly to move the bars 78 and 80 to the dotted line position, which retracts the ends 106 and 108 in the manner shown from the slots 42 and 44, thereby enabling the pan to be moved to the inclined position as indicated in Figure 2.

The bottom 26 of the drain pan may be ribbed crosswise or with shallow corrugated V-grooves as shown in Figure 7 at 109 to provide a somewhat washboard effect, or may be flat as shown. Where V-ribs are provided, extending in an inclined direction, such ribs not only provide for strengthening of the tray, permitting the use of light materials, but also provide drain channels for excess paint squeezed from the roller. It will be appreciated that the apparatus may be made of various light materials, including plastic, as may be desired, and that the overall size may be dictated by the size of the roller to be accommodated.

While a single form of the invention, with a slight modification, has been illustrated and described, it is to be understood that the invention is not limited thereto. As various changes in the construction and arrangement may be made without departing from the spirit of the

invention, as will be apparent to those skilled in the art, reference will be had to the appended claims for a definition of the limits of the invention.

What is claimed is:

- 5 1. A combination paint container and roller pan comprising, a shallow container adapted to hold a quantity of paint or the like for application to a roller applicator, said container having a bottom, and end and side walls, and being open at the top, an imperforate roller pan having side flanges and one end flange, each of said side flanges adjacent the end opposite from said end flange being pivotally secured with respect to said side walls centrally thereof and between the end walls, said pan being pivotally movable from an inclined position adapted to drain into said container, to a substantially upright position with respect to said container, means for positively locking said pan in said upright position, means for unlocking said locking means whereby to move said pan to an inclined position, and a carrying handle on said end flange for carrying the apparatus when said pan is in said upright position, said handle being located so as to be in a position of balance in respect to said container, whereby said container takes a level position when being carried.
- 10 2. A combination paint container and roller pan comprising, a shallow container adapted to hold a quantity of paint or the like for application to a roller applicator, said container having a bottom, and end and side walls, and being open at the top, a pair of upwardly extending ears on opposite sides of the container, an imperforate roller pan having side flanges and one end flange, each of said side flanges adjacent the end opposite from said end flange being pivotally secured to each of said ears, respectively, said pan being pivotally movable from an inclined position adapted to drain into said container, to a substantially upright position with respect to said container, means for positively locking said pan in an upright position, means for unlocking said locking means whereby to move said pan to an inclined position, and a carrying handle on said end flange for carrying the apparatus when said pan is in said upright position, said handle being located so as to be in a position of balance in respect to said container, whereby said container takes a level position when being carried.
- 15 3. A combination paint container and roller pan comprising, a shallow container adapted to hold a quantity of paint or the like for application to a roller applicator, said container having a bottom, and end and side walls, and being open at the top, a pair of upwardly extending ears on opposite sides of the container, an imperforate roller pan having side flanges and one end flange, each of said side flanges adjacent the end opposite from said end flange being pivotally secured to each of said ears, respectively, said pan being pivotally movable from an inclined position adapted to drain into said container, to a substantially upright position with respect to said container, means for positively locking said pan in an upright position, means for unlocking said locking means whereby to move said pan to an inclined position, a carrying handle on said end flange for carrying the apparatus when said pan is in said upright position, said handle being located so as to be in a position of balance in respect to said container, whereby said container takes a level position when being carried, and a tray for holding a roller applicator mounted on said container behind said pan, and adapted to be covered by said pan when in the inclined position.
- 20 4. A combination paint container and roller pan comprising a shallow container adapted to hold a quantity of paint or the like for application to a roller applicator, said container having a bottom, and end and side walls, and being open at the top, a pair of upwardly extending ears on opposite sides of the container, an imperforate roller pan having side flanges and one end flange, each of said side flanges adjacent the end opposite from said
